WEB CONTROLLING DEVICE FOR PRINTING
PRESSES

Allan J. Cline, Chicago, Ill.

Application March 11, 1933, Serial No. 660,398

16 Claims. (Cl. 242—75)

This invention relates to web supply mechanism for printing presses and has for its principal object the provision of a device for improving the quality of the printing by eliminating what is known as "slurring", a difficulty which has been commonly experienced in the printing of newspapers due to vibration of the web at the point of initial contact with the first pair of cylinders in the press. Vibration at this point tends 10 to cause a slight whip of the web against the plates on the plate cylinder almost at the instant the web enters between the first plate and impression cylinders, causing a double impression, with the impressions perhaps slightly out 15 of registration or, in any event, causing the lines of the letters, or some of them, to be wider than they should be, making them appear too black, or slightly blurred. This action is referred to by printers, and herein, as slurring.

I am aware that devices have heretofore been provided having the object of taking up slack 20 in the web between the web roll and the press, these being known as "spring rollers" and consisting of a spring-pressed roller about which the web passes, the springs thereof being compressed 25 by the pull of the web on the roller when it is taut, and tending to press said roller into the web when the latter slackens. The action of such a device is limited, however, by the range of action 30 of the springs and is not uniform, since obviously the springs exert greater pressure on the roller when they are under considerable compression than when they are more extended. It has been found by experience that such devices do 35 not eliminate slurring under certain conditions, whereas under the same conditions it is eliminated by the device of the present invention.

This device, while in the nature of a floating roller, somewhat similar in appearance to the 40 floating rollers which have heretofore been used for controlling brakes or tension mechanism for retarding rotation of web rolls, has a freedom of action and a responsiveness to varying degrees of tautness in the web which causes it to obtain 45 results which are not possible with a floating roller connected with the tension mechanism, namely the virtual elimination of slurring through a responsive, but controlled, action which effectively prevents vibration of the web at the 50 point immediately preceding its entry between the first printing and impression cylinders of the press, and which causes the roller to respond to changes in the degree of tautness of the web without any sudden or uncoordinated action

which might tend to unduly strain or break the web.

Other objects and advantages of the invention will appear from the following detailed description, which, taken in connection with the accompanying drawings, discloses a preferred embodiment thereof.

Referring to the drawings:

Fig. 1 is an end elevational view, partially diagrammatic, of an apparatus in which my invention is embodied;

Fig. 2 is a front elevation of said apparatus on a larger scale, parts thereof being broken away for convenience in illustration;

Fig. 3 is a top plan view of one of the bearings 15 for the shaft upon which the device is supported;

Fig. 4 is an end elevation of said bearing showing the means for adjusting the same; and

Fig. 5 is a sectional view of the dashpot used 20 for dampening the movement of the web-controlling roller hereinafter described.

Upon said drawings I have shown, for purposes of illustration, a roll support in the form of a reel, indicated generally by the reference character 6, said reel having three pairs of arms 7, each carrying a roll 8, said rolls being adapted to be successively moved into the running position shown at the right in Fig. 1. The web 9 from the active roll is directed over a guide roller 11 and about a second roller 12, thence downwardly 30 around a movable roller 13 to be later more particularly described, said web proceeding upwardly from said roller to a third guide roller 14, from which it passes into the press (not shown). It will be noted that the web forms a loop between the rollers 12 and 14, and that the roller 13 rests in said loop so that it may be drawn upwardly by the pull of the web, the extent of which is governed by the relation between the pull of the press and the amount of tension applied to the web roll, the latter, however, not being subject to exact control due to varying conditions such as, for example, the form of the web roll which may not be entirely round, with the result that the paper feeds off faster from 45 the low point than from the high point, or ridge, which is found in lopsided rolls.

Roller 13 is carried in arms 15 which are secured to a shaft 16 supported in bearings 17 and 18, which in turn are supported by angle irons 19 50 and 20 suspended from I-beams 21 and 22 forming a part of the press frame. One of said bearings, in the present instance the bearing 17, is adjustably mounted, being secured by means of screws 23 to a bar 24, one end of which is hinged 55

to ears 25 and the other end of which is formed to receive a screw 26 extending upwardly through the horizontal portion of the angle iron 19, and carrying at its lower end a hand wheel 27 where-
 5 by the operator may rotate said screw to raise or lower the bearing 17. This means for adjustment of the roller makes it possible to change the elevation of one end of the roller 16 with respect to the other in order to maintain a uniform
 10 relation between the roll and the web even though the diameter of the web roll may be different at one end than at the other.

Depending from the shaft 16 is a rod 28 carrying a series of weights 29, the number of which
 15 may be varied to provide more or less effect upon the roller 13 as conditions may require. The normal position of the weight and roller assembly is the lowermost dotted line position shown in Fig. 1 with the weight on the right hand side
 20 of a vertical center line through the shaft 16, in which position the weight serves as a counter-weight preventing the roller 13 from dropping below a certain position. The greater the pull of the web upon the roll 13, the higher said roll is
 25 drawn, the uppermost dotted line position indicating one position which the parts may assume under the pull of the web.

The shaft 16 carries an arm 31 extending in the opposite direction from the arms 15, said arm being connected by a rod 32 with a piston 33 in a dashpot 34 supported on an angle iron 35 rigidly mounted on the frame structure at one end of the reel. The dashpot has screw-threaded end members 36 and 37 at the opposite ends thereof, 30 the latter being provided with an ear 38 adapted to be hingedly attached to ears 39 on the angle iron 35, the end member 36 having a stuffing box 41 therein and gaskets 42 and 43 being positioned between said end members and the ends of the 35 cylinder of the dashpot to render said cylinder oil tight, the oil type of dashpot being perhaps best suited to the purpose of the present device. The piston 33 is provided with an adjustable needle valve 44 adapted to permit the passage of 40 oil in both directions through said piston, the rate of flow, and consequently the speed of movement of the piston, being determined by the adjustment of said valve. A check valve 45 is also provided in said piston, being located in a passageway 46, 45 and is adapted to open upon the up movement of the piston, which, as will be noted by reference to Fig. 1, occurs upon the down movement of the roller 13. A coil spring 47 is provided in the upper end of the dashpot cylinder and serves as a buffer 50 against which the piston 33 may act at the extreme upper end of its stroke. A spring 48 is also provided in the lower end of the cylinder, and serves to provide a yielding stop for the piston at the lower end of its stroke, said spring 55 thereby also preventing the roller 13 from suddenly reaching a dead stop at the upper limit of its movement, thus protecting the web against undue strain or breakage. It will be evident that this spring serves to supplement the weight of 60 the roller 13 and the action of the weights 29 as said roller reaches the upper limit of its movement, and it will be understood that it could be placed elsewhere than in the dashpot, as, for example, on the press frame in position to be engaged by the arms 15 as they approach the upper limit of their movement.

The dashpot hereinabove described serves to dampen the movement of the roller 13 and to prevent any violent action thereof upon the web,

while at the same time allowing it to respond freely to changes in the tautness of the web.

The device of my invention, as above described, has been found to be extremely effective, and for the first time in the art, so far as I am aware, 5 renders it possible, under all ordinary conditions of printing newspapers, to practically eliminate all slurring, thus greatly improving the quality of the printing.

Slurring does not necessarily manifest itself on 10 all pages of newspapers printed without the use of the present device, but its effects are often present on the page printed by the first pair of cylinders in the press. The effect is not always particularly noticeable, since, for considerable 15 periods of time, the web may be held under proper tension, and, furthermore, even when it is allowed to vibrate slightly, it may strike the printing plate so nearly at the point on the web where the normal printing impression is made that it has no 20 other effect than to have the lines appear somewhat wider than they should be. At other times, however, the premature contact of the web with the plates results in an appearance as if the web had slipped a little in passing through the cylinders, with the result that the printing appears to be slightly blurred and is not as easy to read as the clean, sharp-cut printing which may be uniformly produced through the use of the device of my invention, which I therefore term a "slur 25 30 eliminator".

The foregoing detailed description has been given for clearness of understanding only, and no unnecessary limitations should be understood therefrom, but the appended claims should be 35 construed as broadly as permissible, in view of the prior art.

I claim:

1. A web controlling device for printing presses, comprising a movably mounted roller positioned 40 in a loop in the web in advance of the point of entry of the web between the press cylinders, said roller being movable by its weight to take up slack in said web between the web roll and the press and to maintain uniform tautness of 45 the web, thereby eliminating vibration thereof at the point of initial contact of the same with the printing cylinders, said roller being free from connection with tension mechanism for retarding rotation of the roll and being quickly responsive to changes in the tautness of the web 50 irrespective of irregularities in the form of the roll, and a dashpot connected with said roller for dampening the movement thereof.

2. A web controlling device for printing presses, 55 comprising a movably mounted roller positioned in a loop in the web in advance of the point of entry of the web between the press cylinders, said roller being movable by its weight to take up slack in said web between the web roll and the press and to maintain uniform tautness of 60 the web, thereby eliminating vibration thereof at the point of initial contact of the same with the printing cylinders, said roller being free from connection with tension mechanism for retarding rotation of the roll and being quickly responsive to changes in the tautness of the web 65 irrespective of irregularities in the form of the roll, and a dashpot connected with said roller for dampening the movement thereof, said dashpot being provided with an adjustable by-pass valve for controlling the flow of fluid therein in both directions.

3. A web controlling device for printing presses, comprising a movably mounted roller positioned 70 75

- in a loop in the web in advance of the point of entry of the web between the press cylinders, said roller being movable by its weight to take up slack in said web between the web roll and the press and to maintain uniform tautness of the web, thereby eliminating vibration thereof at the point of initial contact of the same with the printing cylinders, said roller being free from connection with tension mechanism for retarding rotation of the roll and being quickly responsive to changes in the tautness of the web irrespective of irregularities in the form of the roll, and a dashpot connected with said roller for dampening the movement thereof, said dashpot being provided with a check valve adapted to open upon movement of the roller in one direction to accelerate such movement. 5
4. A web controlling device for printing presses, comprising a movably mounted roller positioned in a loop in the web in advance of the point of entry of the web between the press cylinders, said roller being movable by its weight to take up slack in said web between the web roll and the press and to maintain uniform tautness of the web, thereby eliminating vibration thereof at the point of initial contact of the same with the printing cylinders, said roller being free from connection with tension mechanism for retarding rotation of the roll and being quickly responsive to changes in the tautness of the web irrespective of irregularities in the form of the roll, and a dashpot connected with said roller for dampening the movement thereof, said dashpot being provided with a check valve adapted to open upon movement of the roller in one direction to accelerate such movement. 10
- 20
5. A web controlling device for printing presses, comprising a movably mounted roller positioned in a loop in the web in advance of the point of entry of the web between the press cylinders, said roller being movable by its weight to take up slack in said web between the web roll and the press and to maintain uniform tautness of the web, thereby eliminating vibration thereof at the point of initial contact of the same with the printing cylinders, said roller being free from connection with tension mechanism for retarding rotation of the roll and being quickly responsive to changes in the tautness of the web irrespective of irregularities in the form of the roll, and a dashpot connected with said roller for dampening the movement thereof, said dashpot being provided with an adjustable by-pass valve for controlling the flow of fluid therein in both directions, and a check valve adapted to open upon movement of the roller in one direction to accelerate such movement. 15

7. A web controlling device for printing presses, comprising a movably mounted roller positioned in a loop in the web in advance of the point of entry of the web between the press cylinders, said roller being movable by its weight to take up slack in said web between the web roll and the press and to maintain uniform tautness of the web, thereby eliminating vibration thereof at the point of initial contact of the same with the printing cylinders, said roller being free from connection with tension mechanism for retarding rotation of the roll and being quickly responsive to changes in the tautness of the web irrespective of irregularities in the form of the roll, a snubber connected with said roller for dampening the movement thereof, and yielding pressure means augmenting the action of the roller against the web upon increase in the tautness of the latter. 70
8. A web controlling device for printing presses, comprising a movably mounted roller positioned in a loop in the web and operable to take up slack in said web between the web roll and the press and to maintain uniform tautness of the web, thereby eliminating vibration thereof at the point of initial contact of the same with the printing cylinders, said roller being free from connection with tension mechanism for retarding rotation of the roll and being quickly responsive to variations in the tautness of the web irrespective of irregularities in the form of the roll, means for dampening the movement of said roller, a weight movable with said roller and adapted to augment the action of the roller against the web when on one side of a vertical center line (with respect to the point of support of the weight) through which the weight passes when the pull of the web on the roller in- 75

creases to a certain degree, and a spring positioned to counteract the pull of the web against the roller as the latter approaches the limit of its movement in the direction in which it is urged by the web.

11. A web controlling device for printing presses, comprising a movably mounted roller positioned in a loop in the web and operable to take up slack in said web between the web roll and the press and to maintain uniform tautness of the web, thereby eliminating vibration thereof at the point of contact with the printing cylinders, said roller being free from connection with tension mechanism for retarding rotation of the roll and being quickly responsive to variations in the tautness of the web irrespective of irregularities in the form of the roll, a weight movable with said roller and adapted to augment the action of the roller against the web when on one side of a vertical center line (with respect to the point of support of the weight) through which the weight passes when the pull of the web on the roller increases to a certain degree, and a spring positioned to counteract the pull of the web against the roller as the latter approaches the limit of its movement in the direction in which it is urged by the web.

12. A web controlling device for printing presses, comprising a movably mounted roller positioned in a loop in the web and operable to take up slack in said web between the web roll and the press and to maintain uniform tautness of the web, thereby eliminating vibration thereof at the point of initial contact of the same with the printing cylinders, a shaft having arms extending therefrom for supporting said roller, a weight mounted on said shaft and disposed at substantially right angles to said arms, said weight serving to augment the weight of the roller when the latter is moved by the pull of the web, and means connected with said arms for dampening the movement of said roller.

13. A web controlling device for printing presses, comprising a movably mounted roller positioned in a loop in the web and operable to take up slack in said web between the web roll and the press and to maintain uniform tautness of the web, thereby eliminating vibration thereof at the point of initial contact of the same with the printing cylinders, a shaft having arms extending therefrom for supporting said roller,

and a weight mounted on said shaft and being movable across a vertical center line (with respect to the point of support of the weight) serving as a counterweight when on one side of said line and serving to augment the roller when on the other side of said line.

14. A web controlling device for printing presses, comprising a movably mounted roller positioned in a loop in the web and operable to take up slack in said web between the web roll and the press and to maintain uniform tautness of the web, thereby eliminating vibration thereof at the point of initial contact of the same with the printing cylinders, a shaft having arms extending therefrom for supporting said roller, a weight carried by said shaft for governing the movement of the roller, and means for adjusting one end of said shaft to cause said roller to maintain a constant relation to the web even though one end of the web roll should be of different diameter from the other, causing the web to unwind unevenly from the roll.

15. A web controlling device for printing presses, comprising a movably mounted roller positioned in a loop in the web and operable to take up slack in said web between the web roll and the press and to maintain uniform tautness of the web, thereby eliminating vibration thereof at the point of initial contact of the same with the printing cylinders, a shaft having arms extending therefrom for supporting said roller, a weight mounted on said shaft at substantially right angles to said roll supporting arms, one of said arms extending beyond said shaft on the side thereof opposite said roller, and a dashpot connected with said extended portion of said arm.

16. A web controlling device for printing presses, comprising a movably mounted roller positioned in a loop in the web feeding into the press and operable to take up slack in said web and to maintain uniform tautness of the web between the web roll and the press, and a weight movable with said roller and adapted to augment the action of the roller against the web when on one side of a vertical line (with respect to the point of support of the weight) through which the weight passes when the pull of the web on the roller increases to a certain degree.

ALLAN J. CLINE.
